(57) **CLAIM**

The ornamental design for an air freshener housing, as shown and described.

DESCRIPTION

FIG. 1 is a perspective view of an air freshener housing; FIG. 2 is a front elevation view of the air freshener housing of FIG. 1;

FIG. 3 is a rear elevation view of the air freshener housing of FIG. 1;

FIG. 4 is a top plan view of the air freshener housing of FIG. 1;

FIG. 5 is a bottom plan view of the air freshener housing of FIG. 1;

FIG. 6 is a right side elevation view of the air freshener housing of FIG. 1; and,

FIG. 7 is a left side elevation view of the air freshener housing of FIG. 1.

The broken lines shown in the drawings are for illustrative purposes only and form no part of the claimed design.

The surfaces or portions not shown in the drawings or described in the specification form no part of the claimed design.
